Primary Examiner — Elizabeth J Oswecki(74) *Attorney, Agent, or Firm* — Muncy, Geissler, Olds & Lowe, P.C.(57) **CLAIM**

The ornamental design for a tree stand, as shown and described.

DESCRIPTION

FIG. 1 is a front elevation view of a tree stand showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is an enlarged portion view taken from encircled portion labeled, "FIG. 6," in FIG. 5;

FIG. 7 is a bottom plan view thereof; and,

FIG. 8 is a perspective view thereof.

The broken line showing is for the purpose of illustrating portions of the tree stand which form no part of the claimed design.

1 Claim, 8 Drawing Sheets(56)
